UNITED STATES PATENT OFFICE.

S. GODFREY, LOREN BARNES, HENRY BLISH, AND SOLOMON S. SMITH, OF NORTH FAIRFIELD, OHIO.

IMPROVEMENT IN STILLS.

Specification forming part of Letters Patent No. 28,939, dated June 26, 1860.

To all whom it may concern:

Be it known that we, SOLOMON GODFREY, LOREN BARNES, HENRY BLISH, and SOLOMON S. SMITH, of North Fairfield, in the county of Huron and State of Ohio, have invented a new and useful Improvement in Stills for Running Beer and High Wines; and we do hereby declare that the following is a full, clear, and exact description of the same, reference being had to the accompanying drawings, forming a part of this specification, in which—

Figure 1 represents a vertical, and Fig. 2 a horizontal, section of the apparatus.

Similar letters of reference in each of the several figures indicate corresponding parts.

The nature of our invention consists, first, in the combination of three or more chambers of a still with bent tubes, radiating perforated tubes, and straight tubes, when arranged in relation to each other, as will be set forth in the following specification.

It consists, second, in the combination of the same with the heater and doubler, as herein-after specified.

The object of this arrangement is to divide the beer or high wines into different layers, each to be heated separately by steam passing from the bottom upward through the liquid, thereby effecting a more thorough and rapid distillation than by distributing the liquid in one body.

To enable others skilled in the art to make and use our invention, we will proceed to describe its construction and operation.

The still, as represented in the drawings, is divided into three separate chambers, E F H. An additional heating-tub, A, connects with the upper chamber, H, by means of a tube, J. The chambers H and F and F and E are connected by pipes K L, respectively, each of these pipes passing through the bottom, dividing one chamber from the next one. Each of the pipes K L extends some distance above the dividing-bottom, and terminates below this dividing-bottom near the bottom of the chamber below. A series of perforated pipes, O, (the perforations opening upward,) radiating from the end of upright tubes I G, are arranged upon the bottoms of chambers H and

F. The tubes I G are bent so that their other ends pass downward through the bottoms of their respective chambers. The chambers H and F have also openings closed by valves S T. The lower chamber, E, has near its bottom two openings, one closed by a stop-cock, M, the other communicating with a steam-generator by means of a pipe, D. A pipe, P, leads from chamber H into the doubler Q, which latter communicates with a condenser by means of a pipe, R. The liquid to be distilled is forced through pipe B into heating-tub A, where it is heated by the steam entering through pipe C. The liquid passes from A through pipe J into the upper chamber, H of the still, where it rises to a level with the upper extremity of tube K, and then passes through tube K into the middle chamber, F. It fills this chamber to a level with the upper end of tube L, and flows then through tube L into the lower chamber, E. The liquid while in the chambers of the still receives additional heat from the steam entering the lower chamber, E, through pipe D. The steam after passing through the liquid in chamber E passes through pipe G into radiating-pipes O, and through their perforations and through the liquid in chamber F, and passes from this chamber F in a similar manner through pipe I and perforated pipes O into and through the liquid in chamber H, and finds its way through pipe P into the doubler Q, and thence finally into the condenser. When during this process of distilling the lower chamber becomes nearly filled, the slop can be let off by opening stop-cock M, taking care to allow enough to remain in the chamber E to cover the lower end of tube L.

It will be understood that the proof can be regulated to any desired percentage by decreasing or increasing the action of the pump forcing the liquid through pipe B into heater A, and thereby confining a given quantity of liquid a longer or shorter time in the various chambers of the still.

When it is desired to discontinue the process or to clean the still, the valves S T are opened, so as to let the contents of chambers H F pass down into chamber E, wherefrom

they may be drawn off by opening stop-cock M.

What we claim as our invention, and desire to secure by Letters Patent, is—

1. The combination of three or more chambers of a still with bent tubes I G, radiating perforated tubes O, and straight tubes K L, when arranged in relation to each other, substantially in the manner and for the purposes set forth.

2. The combination of the above with the

heater and doubler, in the manner and for the purpose set forth.

SOLOMON GODFREY.
LOREN BARNES.
HENRY BLISH.
SOLOMON S. SMITH.
